UNITED STATES PATENT OFFICE.

LINCOLN C. CUMMINGS, OF PORTLAND, MAINE.

TRUCK FOR CARS OR OTHER VEHICLES.

SPECIFICATION forming part of Letters Patent No. 618,028, dated January 17, 1899.

Application filed October 24, 1898. Serial No. 694,357. (No model.)

To all whom it may concern:

Be it known that I, LINCOLN C. CUMMINGS, a citizen of the United States, residing at Portland, in the county of Cumberland and 5 State of Maine, have invented certain new and useful Improvements in Trucks for Cars or other Vehicles; and I do hereby declare the following to be a full, clear, and exact description of the invention, such as will enable others skilled in the art to which it 10 appertains to make and use the same.

My invention relates to improvements in trucks for cars and other vehicles; and it is especially designed, first, to cause the car to be moved much more easily and with, at least, 15 half the present friction on the track, and, second, to bring the car-body nearer the track.

It consists of a truck-body provided with channels closely resembling in configuration 20 the Arabic figure 8, except that one portion of the channel travels over the other, the channel not being in the same horizontal plane. Adapted to run in these channels are suitable spheres, globes, or balls, some of the 25 number always traveling through an opening in the bottom of the truck and in contact with each rail to sustain the weight of the car.

It further consists of means for preventing the channel from becoming filled with snow 30 or ice and means for holding the truck on the track.

In the drawings herewith accompanying and forming a part of this application, Figure 35 1 is an inverted plan view of my device, arrows indicating the movement of the balls. Fig. 2 is a section taken on line X X of Fig. 1. Fig. 3 is a section taken on line Y Y of Fig. 1, and Fig. 4 is a section taken on line Z Z of Fig. 1.

40 The same letters refer to like parts in all the figures.

In said drawings, A represents a truck-carriage. This may be made in any suitable manner; but I prefer to provide it with a top 45 plate B and a bottom plate C for convenience in making a channel, hereinafter mentioned, therein. These plates are firmly attached to the carriage by means of suitable bolts D. This carriage is provided with a channel E, 50 substantially of the configuration of the Arabic figure 8, having at its outer extremi-

ties and at the bottom thereof openings F, provided with a flange G. Adapted to travel in the channel are balls or spheres H. The said balls H are so arranged that when they are 55 presented through the opening F a fraction of their diameter is exposed to contact with the rail. By this means the truck-carriage is raised sufficiently from the track to clear all ordinary obstacles and will not interfere 60 with switches, &c. At each end of the carriage and rigidly attached thereto are shafts I, on which are adapted to revolve flanged wheels J. These wheels are not usually intended to carry the weight of the car; but the 65 flanges simply serve the purpose of keeping the truck on the rail when rounding curves or taking switches, but revolving when they strike the rail or switch. They further serve to prevent a lateral motion of the truck when 70 being carried at a high rate of speed. These trucks, like loose pulleys, are adapted to revolve upon their axes, when necessary. These trucks may be made of rubber, wood, or other suitable material and are made sufficiently heavy, should the exigency require, 75 to carry the weight of the car. To accomplish this, it is my intention to have their axles so arranged as to be capable of a vertical adjustment. The top portion O of the 80 channel E, near the opening F, may be made thicker than the other portion of the groove, for the purpose of guiding the balls downwardly and through the opening when, 85 through the movement of the cars, the balls are brought into motion. The groove is made with square surfaces, so that the balls may have a smooth and unobstructed path to travel, the greatest number of contact-points at any one time being three, for the special 90 reason that the groove being of greater depth than the diameter of the balls the balls when in motion will touch only on the sides and the top or bottom during their course of travel.

When the car is moved, it will be seen that 95 there will be a number of the balls at each end of the truck that will sustain the weight of the truck and car and bear upon the track, the extent of the bearing on each track corresponding to the length of the bearing of the 100 ordinary railway-car truck at each end of the car between the front and rear wheels of each

truck-frame. As the truck is moved forward the balls contained in the opening and in contact with the track revolve on their own axes in the same direction as that taken by the moving truck, so long as the balls are in contact with the track. As soon, though, as the contact is released the ball then passes into the channel E and revolves on its axis in the opposite direction to that taken by the truck but in the same direction that the ball itself travels, as shown by the arrows in Fig. 1. This motion is continued until the opposite opening is reached, when the ball, again descending to the track, takes motion in the same direction as the movement of the truck. Thus it will be seen that the balls have two distinct and opposite movements on their own axes, but they also continually travel in a direction, as to the truck itself, opposite to the direction taken by the truck. For example, as the truck is moved forward the balls revolve not only upon their own axes and in the same direction as the car but also travel in a direction opposite to that taken by the car. As these balls move, for example, backward, by the car traveling faster than the balls, above cited, they will travel through the channel up over the inclined portion marked K in Fig. 3 and by the force of other balls coming into place to supply the vacancy caused by those already moved out of position these first-named balls are caused to travel through the circulatory channel until the balls come into operation at the opposite end of the truck, constantly rotating upon their own axes in the manner and direction as before related. The same principle applies to the balls thus fed and supplied to the opening on the opposite side, and the motion caused by the movement of the train and the revolution of the balls in the bearing gives a continuous motion all in the same direction. In order to prevent snow or moisture freezing in the channel choking it and preventing the balls from traveling readily in the proper direction, I insert at the opening L a small steam-pipe, which follows the configuration of the channel in the truck and has an inlet and an outlet at the point M, as shown in the drawings. This pipe can be kept heated by steam from the locomotive and connected thereto by suitable couplings.

Instead of arranging the channel as shown—that is, making one continuous path through which the balls may travel from one opening to another—I can use two independent channels substantially circular or oblong in form and in the same plane, the two circles having no connection with each other. In practice, though, I find this arrangement not as satisfactory, as the balls are more liable to bind when forced to travel in circles rather than in the elliptical lines of my preferred form, where they cannot bind and have a double feed for each rail and are always presented to and leave the track in a line in the

direction of the moving truck. This, it is evident, prevents any momentary stoppage of the ball in its revolution on its own axis and its movement through the opening. In order to show that my device will save in wear over the ordinary car-truck, it is only necessary to follow the course of one of the balls from the time it is in contact on the rail until it reaches the opposite side of the frame. In the ordinary car-wheel as long as the car is in motion the wheels are continually carrying the weight, while in my device the rotating and receding balls sustain the weight and are subjected to a wearing pressure only momentarily when they are exposed in the openings. The remainder of the time they simply travel through the channel and are subjected to no especial wear save that very minute amount caused by the balls traveling through a practically frictionless channel. In other words, the ball is subject to a wearing process but twice during its course of travel from one opening to the other. The opening in the bottom of the carriage can be made of sufficient length to accommodate any number of balls to sustain the weight of the truck and car, the greater number of balls diminishing in proportion the weight on each individual ball and at the same time greatly diminishing the friction. It will also be seen, and I have proved by experiments, that the distance traveled by the truck and car itself as compared to the distance traveled by an individual ball thus circulating is as three to one, thereby largely overcoming all friction.

The advantages of my invention are that it largely overcomes the friction and also brings the car down nearer the track, bringing consequently the center of gravity lower, allowing a greater speed and lessening the power of centrifugal force on the cars. A further advantage is that it provides a smooth, easy-running truck, which with present power applied to a given number of cars will at least double the speed now obtainable, first, by thus overcoming friction, and, second, from the fact that the center of gravity is brought nearer the track, allowing greater speed in making curves, &c.

Having thus described my invention and its use, I claim—

1. In a truck, a suitable bed, a channel in said bed, a series of balls adapted to circulate in said channels, said balls having a motion upon their own axes in the direction of the movement of the truck during part of the space traveled and a direction opposite to the movement of the truck for the rest of the way, substantially as and for the purposes set forth.

2. A new article of manufacture, a car-truck having a suitable bed, openings in the bottom of said bed at each extremity thereof, a channel substantially in the form of the Arabic figure 8 joining said openings, a series of balls adapted to circulate through said

channel and into said openings, substantially as and for the purposes set forth.

3. In a truck, a suitable bed, openings at each end at the bottom thereof, a continuous 5 circulating-channel substantially of the configuration of the Arabic figure 8 extending across the truck, all parts of the channel not being in the same horizontal plane, connecting said openings, and a series of rotary globes 10 or spheres adapted to travel within said channel, and successively bear the weight of the truck, substantially as and for the purposes set forth.

4. In a truck for railway-cars or other vehicles, a bed having an endless channel therein 15 substantially of the configuration of the Arabic figure 8 and extending across the truck, all points of said channel not being in the same horizontal plane, openings at opposite points in said truck connected with said channel, a series of freely-moving balls or 20 spheres adapted to circulate through said channel from one opening to the other and rotating flanged pulleys adjustable vertically for preventing lateral displacement of said truck substantially as and for the purposes set forth.

25 5. In a truck, a suitable bed, circulating-channels extending across said truck, openings in said bed at opposite sides and in the

bottom thereof and a series of freely-moving balls or spheres adapted to circulate within said channels and through said openings, said spheres or balls when traversing said openings sustaining the weight of the superimposed bed, substantially as and for the purposes set forth. 35

6. In a car-truck, a suitable bed, an endless channel therein substantially of the configuration of an Arabic figure 8 and extending 40 across the truck, all points of said channel not being in the same horizontal plane, openings at opposite points on said truck connected with said channel, a series of freely-moving balls or spheres adapted to circulate 45 through said channel from one point to the other, rotating flanged pulleys adjustable vertically for preventing a lateral displacement of said truck and means for preventing said balls from being clogged by snow or 50 ice, substantially as and for the purposes set forth.

In testimony whereof I affix my signature, in presence of two witnesses, this 20th day of October, A. D. 1898.

LINCOLN C. CUMMINGS.
